TRAFFIC REGULATING SYSTEM

Paul P. Horni, Newark, N. J.

Application July 19, 1932, Serial No. 623,338

15 Claims. (Cl. 177—337)

This invention relates to an automatic traffic regulating system and has particular reference to a system of the type whose signals are subject to control by the traffic.

5 In my co-pending application Serial No. 484,334, filed September 25, 1930, there is disclosed an automatic traffic regulating system for a street or road intersection, which is normally inactive and whose signal lights are normally extinguished so as to dispatch traffic along one street at the intersection without interruption by traffic control and which is arranged to become operative by a unit traffic approaching the intersection on one of the other streets. When the operation of the apparatus is so initiated by a unit of traffic approaching the intersection on one of the cross-streets, the signal lamps are illuminated and the usual signal cycle is completed before the system again lapses into inactivity and the signal lamps are again extinguished. This condition normally obtains at all times until traffic from a cross-street again seeks to traverse the intersection.

In another form of traffic control system, clear signals are normally illuminated along the main highway or street having the greatest flow of traffic so as to dispatch the traffic, while the traffic on the cross-street intersecting the main highway is normally halted by a "stop" signal. The system is rendered active by traffic approaching the intersection on the cross-street and the usual signal cycle is completed to temporarily stop the main highway traffic and permit the cross traffic to cross or enter the main highway. Thereafter the signal system again lapses into inactivity, that is to say, the clear signal is steadily indicated to main highway traffic and the "stop" signal is steadily indicated to cross traffic.

In the traffic control systems disclosed in my aforementioned co-pending application, the traffic approaching the intersection or main highway is not sufficiently warned of the dangerous intersection ahead. For example, if the signal lamps of the mechanism are normally extinguished, there is nothing to warn a vehicle speeding along the main highway of the approaching intersection, and frequently a vehicle turning into or crossing the main highway from a side street forming the intersection will not wait until the signal cycle is sufficiently advanced to flash a "go" or clear signal, but will turn into or seek to cross the main highway and thus provoke a serious collision with speeding main highway traffic.

55 Likewise, in the case where the normally clear

signal is steadily indicated along the main highway, a right-turning vehicle from a cross-street is likely to collide with a speeding vehicle on the main highway. Also, as in the case mentioned above, many operators of vehicles approaching the intersection in the cross-street will not wait for the traffic system to give the clear signal in response to the actuation of the system by their vehicles, but will enter the main highway seeking to make a right or left turn or cross it and thus 10 endanger themselves and the occupants of vehicles approaching along the main highway.

It is a principal object of this invention to provide both of the normally inactive systems mentioned with auxiliary warning signals to inform 15 the vehicles approaching the intersection from one or more or all directions that an intersection under automatic traffic control lies ahead. In this way, the aforementioned normally inactive traffic control systems are rendered more effective 20 for preventing accidents and collisions during their periods of normal inactivity, and provide a form of continuous warning signal despite the fact that the signal cycle is normally inactive, so as to dispatch traffic along the main highway. 25 Thus, the present system has all the advantages of the normally inactive, vehicle-actuated traffic control system, plus the advantages of the continuous traffic control system, without involving the objections to the former, that is, unidentified 30 street intersection, nor the objections to the latter, that is, the intermittent stopping of traffic along a main highway when there is no cross-travelling traffic seeking to cross the main highway or turn into it.

35 This object is attained in a preferred embodiment of the invention, which preferably includes a traffic control mechanism which is normally inactive, so as to dispatch traffic along a main highway or other road or street having a considerable flow of traffic, and which is rendered 40 operative to stop the main highway traffic by a vehicle approaching the intersection from a side or cross street so as to permit this crossing vehicle to negotiate a turn into or cross the main highway. 45 This system returns to its normally inactive state automatically upon completion of the signal cycle after permitting the cross-travelling vehicle to enter or cross the main highway, but the mechanism which completes the signal cycle in this 50 fashion establishes another signal circuit automatically, which provides a continuous warning signal to traffic approaching the intersection from one or more or all directions.

More particularly, the mechanism which re- 55

stores the traffic control system to its normally inactive state closes a switch which, depending upon the selection of traffic lamps previously made, effects the actuation of circuit interrupting devices interposed in the circuits of the signal lamps so selected. Accordingly, the selected signal lamp or lamps flash intermittently during the entire time that the principal signal system is inactive, so as to warn vehicles approaching from that particular direction of the dangerous intersection directly ahead. By means of a manually adjustable selector switch this selection may be made, whereby various combinations of traffic lamps intermittently flash the warning signal in different directions. For example, one position of the selector switch may cause the amber or caution lamps to flash in all directions; another position of the selector switch may cause the caution or amber lamps on the main highway and the red or "stop" lamps on the cross-street or streets to flash intermittently; another position of the selector switch may cause the amber or caution lights on the main highway to flash intermittently and the red lamps on the cross-streets to shine steadily; another position of the selector switch may cause the main highway clear or green lamps to flash intermittently and the cross-street red or "stop" lamps to flash intermittently; while for another position of the selector switch the main highway clear or green lamp and the cross-street red or "stop" lamp may shine steadily, while the main highway and cross-street caution or amber lamps flash intermittently. Obviously, many other combinations may be obtained for securing different flashing warning signal effects, and it is to be understood that such combinations lie within the scope of the invention.

This intermittent flashing action of the lamps to constitute a warning signal at the intersection, ceases immediately upon energization of the master signal system when a vehicle approaching the intersection on the cross-street closes the vehicle-actuated switch. The intermittently flashing warning signal remains inactive during the normal signal cycle initiated by cross-travelling traffic but, as soon as the signal cycle thus initiated is completed, instead of lapsing into complete inactivity, as is now the case, the intermittent signal mechanism immediately comes into action to maintain a flashing warning signal against traffic approaching on one or more or all streets or roads constituting the intersection.

It will be seen that the automatic traffic regulating system of this invention constitutes a valuable adjunct to the present forms of normally inactive, vehicle-actuated types of traffic signal systems, such as are described in my co-pending application. The intermittent warning signal mechanism may be attached to either of the existing systems mentioned without great change and without great cost, inasmuch as the original circuits are not changed materially nor are many additional parts necessary, such parts constituting the interrupter mechanism, the manual selector switch and the relays controlled by the manual selector switch for selecting the various combinations of intermittently signalling lamps to the exclusion of the remaining lamps. It is to be understood, however, that the intermittent signal mechanism of this invention is not necessarily a separate system, but forms part of a complete traffic control system, and should be considered as such, although wherever possible it may be applied as an auxiliary to the existing traffic control systems of the type described.

For a better understanding of the invention, reference may be had to the accompanying drawings, in which—

Fig. 1 is a circuit diagram of an automatic traffic control system of the type whose signal lamps become extinguished upon completion of the signal cycle, this system including as a part the auxiliary intermittent signalling arrangement; and

Fig. 2 is a circuit diagram of a traffic control system of the type which normally lapses into inactivity after completion of a signal cycle to indicate a clear signal to main highway traffic and a "stop" signal to cross-street traffic, this system including the auxiliary intermittent signalling arrangement.

In these drawings a simple case of two streets or roads intersecting at right angles has been selected in the interests of simplicity and clarity. It is to be understood, however, that the system of this invention is applicable with equal facility to streets or roads which do not cross at right angles, two or more intersecting streets or roads, streets or roads forming a T-shaped, L-shaped or Y-shaped intersection, more than two streets or roads forming a star-shaped intersection, and peculiar intersections constituting streets running together from any and all directions, whether or not these are through streets, and the like. Also, in the particular cases selected for illustrating the invention, one of the streets is considered to be the main highway, along which traffic is despatched without being interrupted by the traffic control signals, except when traffic approaching the highway on the cross-street initiates the signal cycle by closing either contacts 23 or 23' in Fig. 1, or contacts 230 or 230' in Fig. 2. Accordingly, in any case it is assumed that the main highway traffic is heavy and flows substantially steadily during the rush hours and, therefore, it is desirable to despatch it as quickly as possible, while the traffic on the cross-street is relatively light and not steady, so that it is more feasible to despatch this cross-traffic when, as, and if it appears, whereby the main highway traffic is interrupted only in these circumstances.

The circuit diagram of Fig. 1 includes a master signal system of the general type disclosed in my afore-mentioned co-pending application, that is, one in which no traffic lamps are illuminated except when the signal cycle is initiated by the closure of either one of the street contacts 23 or 23' by a cross-travelling vehicle, and this system is provided with the auxiliary system having the added feature that, upon completion of the signal cycle so initiated, the intermittent flashing of lamps in one or more or all directions is procured continuously, until the master signal cycle is again energized to cross-travelling vehicles engaging either contacts 23 or 23'. Accordingly, instead of lapsing into total inactivity by complete extinguishment of all traffic lamps, only the master signal system lapses into inactivity upon completion of the signal cycle, but the intermittent signal begins immediately thereafter.

The circuit diagram of Fig. 2 is of the general type of automatic traffic control system in which the signalling cycle of the master system is initiated by a cross-travelling vehicle actuated by either of street contacts 230 or 230', and after the signal cycle is completed the green or clear lamp is displayed steadily to main highway traffic and the red or "stop" light is displayed to cross-travelling traffic, and this system is provided with the auxiliary system having the additional feature

that the intermittent flashing signal becomes operative upon completion of the master signal cycle and continues until the master signal system is again energized by the closing of either of 5 cross-street contacts 230 or 230' by a second cross-travelling vehicle.

While these two types of master traffic control systems are the only normally inactive types now known to me, it is to be understood that the invention may be applied with equal facility to other 10 forms of traffic control systems which have lapses of inactivity at any time.

Referring to the circuit diagram of Fig. 1, let 15 it be assumed that a vehicle is approaching the intersection from the north and that just before the vehicle reaches the intersection it closes street contacts 23. It will be recalled that in this system no traffic lamps are displayed in any direction under normal circumstances and that the system 20 is normally inactive in every sense of the word. This actuation of street contacts 23 closes a circuit 25 traceable from battery 20, closed line switch 21, wire 22, street contact 23 closed by the cross-travelling vehicle, relay 25, wire 26' and wire 26 30 back to battery 20. Relay 25 pulls down its armature 25' to bridge contacts 27, closing a circuit 35 traceable from battery 20 through wires 22 and 28, contacts 27 of relay 25, armature 25' thereof, terminal 29, where the circuit divides, one 40 branch leading to relay 32 and wires 34, 45 and 26 back to battery 20, while the other branch follows wire 31, relay 33 and wires 45 and 26 back to battery 20. Relay 32 pulls down its armature 36 to bridge contacts 37 and this 45 armature 36 is locked in closed position by pawl 38. Similarly, relay 33 pulls down its armature 39 to bridge contacts 40 and the armature 39 is locked in closed position by the pawl 41. Both relays 32 and 33 control the circuit of 50 motor A, the circuit including the contacts of relay 32 being traceable from battery 20, wires 22 and 42, contacts 37, armature 36 of relay 32, wires 42' and 43, motor A and wires 44 and 26 back to battery 20. The circuit including the contacts of 55 relay 33 may be traced from battery 20 through wire 22, wire 22', contacts 40 of relay 33, armature 39, wires 19 and 43, motor A and wires 44 and 26 back to battery 20. It will be seen that the contacts 40 of parallel relay 33 are in parallel 60 with the contacts 37 of relay 32 and that, if the contacts of relay 32 are opened, the motor A circuit is maintained so long as the contacts of relay 33 are closed.

As the motor A begins to rotate, cam 50, 55 mounted on cam shaft 51 and driven by motor A, drops its follower 52 off of its high point 53 to the no motion surface thereof, which comprises the greater portion thereof. This action causes 60 spring contacts 54 to close, which initiates the signal cycle operation. Also, contacts 61 of cam 60 are closed, and follower 66 lies in the notch of cam 67 and contacts 85 are closed, while contacts 68 are open.

It will be recalled that wire 43 was energized by 65 relay 32 when cross-street contacts 23 were closed. Therefore, beginning with wire 43, a circuit may be traced through wire 55, closed contacts 54, follower 52, wires 56, 57 and 62, follower 58 of cam 69, closed contacts 61, wire 63, and follower 70 66 of cam 67 where the circuit divides. One branch of this circuit from follower 66 follows wire 74 to back contact 75 of relay 76. The back contact 75 of relay 76 is normally engaged by armature 77, so that the circuit completed there- 75 by follows wire 78 to back contact 79 of relay 49,

which is normally connected to wire 82 by the normally closed armature 80 of relay 49. Wire 82 leads to the cross-street red lights 83, which are connected to the other side of battery 20 by wire 64 and wire 26. Cross red lights 83 are accordingly illuminated. The other branch of the circuit from follower 66 of cam 67, runs through closed contacts 85, wire 86, normally closed back contact 87 of relay 88, armature 89 thereof, wire 90, main amber lights 91 and wires 48 and 26 10 back to battery 20. It will be seen that the warning amber lights 91 are displayed to main highway traffic and the red stop lights 83 are simultaneously displayed to cross-travelling traffic, including the vehicle which initiated the signals by 15 closing street contacts 23.

As the cam shaft 51 rotates further follower 58 rides up on the high point 59 of cam 60 to disconnect contacts 61, thus breaking the circuit previously traced to main amber lights 91 and 20 cross red lights 83 and extinguishing them. Simultaneously, the follower 92' of cam 92 drops into the notch thereof and closes contacts 93, thus completing a circuit from energized wire 43, wire 55, closed contacts 54 of cam 50, its follower 25 52, wires 56, 57 and 94, follower 92' of cam 92, closed contacts 93 to terminal 106, where the circuit divides, one branch following wire 107 to solenoid 108 and wires 84 and 26 back to battery 20. 30

Energization of solenoid 108 withdraws locking pawl 38 and releases armature 36 of relay 32 to break the circuit across contacts 37 and through wire 43 to motor A, which, it will be recalled, was energized by the closing of street contacts 23 by 35 the cross traffic. The circuit of motor A is maintained, however, through the aforementioned parallel circuit established by relay 33, this circuit being traceable from battery 20, wires 22 and 22', contacts 40 and armature 39 of relay 33 and 40 wires 19 and 43 to motor A, so that the motor keeps on rotating without interruption, though its master relay 32 was reopened.

The other branch circuit from terminal 106 45 may be traced through wires 111 and 109 to main red lights 110 and back to battery 20 through wires 48 and 26. Illumination of red lights 110 accordingly stops main highway traffic.

Another branch circuit from terminal 106 50 may be traced through wire 111, follower 112 of cam 50, 113, closed contacts 114, wire 115, cross-street green lights 116, and back to battery 20 through wire 26. Thus, cross traffic receives the "go" signal from green lights 116 and main highway traffic simultaneously receives the "stop" signal 55 from the red lights 110.

The followers of cams 60 and 113 subsequently drop off the high points thereof and close contacts 61 and 117, respectively, and cam 113 also opens contacts 114, so that the circuit to cross green 60 lights 116 is broken while the main red lights 110 remain energized. The circuit initiated by the closing of contacts 117 may be traced from energized wire 43, wire 55, closed contacts 54 of cam 50, its follower 52, wires 56, 57 and 94, closed contacts 93 of cam 92, terminal 106, wire 111, contacts 117 of cam 113, wire 118, normally closed back contact 119 of relay 120, armature 121 thereof, wire 122, cross-street amber lights 123 and wire 26 back to battery 20. Thus, the cross- 70 street green lights 116 are extinguished and the cross-street amber lights 123 are simultaneously lighted.

Now, referring to the closure of contact 61 by cam 60, this action takes place an instant after 75

the action of cam 113 and effects the illumination of cross red lights 83 and main amber lights 91. This circuit is traceable from energized wire 43, wire 55, contacts 54 of cam 50, wires 56, 57 and 58, closed contacts 61 of cam 60, wire 63, follower 66, where the circuit divides, one branch running through closed contacts 85, contact 87 of relay 88, its armature 89 and wire 90 to main amber lights 91, while the other branch circuit follows wire 14, back contact 75 of relay 76, its armature 77, wire 78, back contact 79 of relay 49, its armature 81, wire 82, cross red lights 83 and back to battery 20 through wires 64 and 26.

Immediately thereafter, the follower 92 of cam 92 rides upon the no-motion surface of the latter and opens contacts 93. The opening of contacts 93 breaks the circuit through the main red lights 110 and the cross amber lights 123 which had been energized by the closure of contacts 117 of cam 113. The opening of contacts 61 also de-energized reset coil 108 of relay 32 so that it is ready for the next setting action.

Immediately after the action just described, the follower 66 of cam 67 rides up on the no-motion surface thereof to open contacts 85 and close complementary contacts 68, to extinguish main amber lights 91 and illuminate green main lights 125, while cross red lights 83 remain illuminated. Thus main highway traffic is restored and cross-street traffic is stopped by the red lights 83 after having passed the vehicle which initiated the signal action by closing cross-street contacts 23 or 23'. Fig. 1 illustrates this condition of the traffic control system.

Meanwhile, the motor A continues to rotate until follower 126 of reset cam 127 drops into the notch 128 thereof to close contacts 129. The circuit thus established is traceable from battery 20, wires 22 and 22', contacts 40 of relay 33, wires 19 and 55, contacts 54 of cam 50, wires 56, 57 and 130, contacts 129 of cam 127, wire 131, reset solenoid 114 and wires 45' and 26 back to battery 20. Energized solenoid 114 pulls pawl 41 from armature 39 to release it, so that the connection between contacts 40 is broken, thus deenergizing the entire system. Motor A accordingly stops rotating and all traffic lights are extinguished so that main highway traffic can continue without interruption, inasmuch as the signal system is controlled only by the cross traffic. As the motor A stops, the follower 52 rides up on the high point 53 of cam 50 to disconnect contact 54, whereby the system is restored to its initial position and is ready for a successive cycle of operation initiated by a cross-traveling unit of traffic closing either contacts 23 or 23' on the cross street.

Assume that the manual selector switch 154 is open, that is, that its arms 165 and 166 are not engaging any of the respective contacts 169, 170, 171 or 172, 173, 174. Under these conditions, the main amber lights 91 are caused to flash, as will now be explained. When the follower 52 rides up on the high point 53 of cam 50 an insulated lever 132 on its follower 52 forces spring contact 133 into engagement with contact 134. This closes a circuit traceable from battery 20 through wires 22 and 135, contacts 133 and 134, closed line switch 140 to terminal 136, where the circuit divides, one branch following wires 137 to terminal 138, where the circuit again divides, one branch leading to motor B and back to battery 20 by way of wire 141, while another branch leads from terminal 138 to contactor 143 having a follower 144, which rides on interrupter cam 145.

driven by the motor B by means of shaft 146. Contact 143 is engaged and disengaged from contact 142 by the action of cam 145 in a manner readily understood. A condenser 148 in parallel with contacts 143 and 147 prevents arcing between them when they are separated by cam 145.

It will be recalled that the circuit divides at terminal 136 and the other branch of this circuit follows wire 150 to terminal 153 of manual selector switch 154, which is a double-pole, multiple-throw switch, whose purpose will be described later. Another branch circuit from terminal 153 leads to relay 88, which is accordingly energized and pulls down its armatures 89 and 89', 15 and bridges front contact 163. This holding circuit is completed through wires 160 and 26 to battery 20.

Likewise the make and break contact 142 is connected by wire 156 to terminal 157 where it 20 divides, one branch leading to the other terminal 158 of manual selector switch 154, while the other branch leads from terminal 157 and follows wire 159 to contact 163 of relay 88, its armatures 89' and 89, wire 90, main amber lights 91, 25 and wires 48 and 26 back to battery 20.

It will be seen that the intermittent interruption of this circuit by cam 145 periodically makes and breaks the circuit to the main amber lights 91, so that they continuously flash a warning signal to the main highway traffic, all other traffic lights directed to main and cross traffic remaining extinguished. Thus, although the traffic control mechanism lapses into inactivity at the completion of the signal cycle, the main amber lights 35 flash intermittently to warn main highway traffic of the intersection. When a cross-traveling vehicle closes contacts 23 or 23', the subsequent energization of the signal system operates motor A, so that cam 50 disengages contacts 133 40 and 134 to stop the motor B and the flashing of main amber lights 91.

The flasher may be disconnected if desired by opening the switch 140. With this switch open and the motor deenergized, no traffic lamps are 45 displayed in any direction. When the motor A stops, contacts 54 of cam 50 are opened and accordingly no energizing current from the wire 22 can reach the various signal lamps since such current is supplied solely through these contacts 50. 54 when the switch 140 is opened.

Now referring to the two-pole, multiple-throw manual selector switch 154, it will be seen that it comprises two switch arms 165 and 166, pivoted to terminals 158 and 153, respectively, and connected by non-conductor bar 167 bearing the handle 168. By moving the switch by means of handle 168, each of its arms 165 and 166 may be connected to one of three contacts, the former engaging either contacts 169, 170 or 171, and the latter engaging either contacts 172, 173 or 174. Thus contacts 172 and 169, contacts 173 and 170, or contacts 174 and 171 may be simultaneously connected to the corresponding switch arms 165 and 166, respectively. Each of these combinations obtains a different flashing signal effect.

For example, assume that the switch 154 has been thrown so that arms 165 and 166 engage contacts 169 and 172, respectively, as illustrated in Fig. 1. One circuit completed by this position 70 of the switch 154 is traceable from battery 20, wire 135, contacts 133 and 134 of cam 50, wire 150, terminal 153, switch arm 166, contact 172, wire 175, relay 120, and wires 161 and 26 back to battery 20. Energized relay 120 pulls its arm- 75

ture 121' into contact with front contacts 176, and breaks contact between its back contact 119 and its armature 121. A flashing circuit is accordingly completed from terminal 157 through 5 switch arm 165, contact 169, wire 177, relay contacts 176, armatures 121' and 121, wire 122, cross amber lights 123, and wires 151 and 26 back to battery 20. Accordingly, inasmuch as main 10 amber lights 91 are already flashing, both main 15 amber lights 91 and cross amber lights 123 flash intermittently in all directions so as to warn traffic of the intersection and cause it to slow down.

If the selector switch 167 is moved so that its 5 arms 165 and 166 engage contacts 170 and 173, respectively, the aforementioned circuit through relay 120 is broken and the normal contact between its armature 121 and back contact 119 is restored. This position of the selector switch 0 closes a circuit traceable from battery 20, wire 135, closed contacts 133 and 134 of cam 50, wire 150, terminal 153, switch arm 166, contact 173, wire 181, relay 49 and wires 152 and 26 back to battery 20. Energized relay 49 pulls its armature 80 out of engagement with back contact 79 and its armature 80' into engagement with front contacts 182. This establishes a flashing circuit traceable from terminal 157, switch arm 165, contact 170, wire 183, relay contact 182, armatures 0 80' and 80, wire 82, cross red lights 83 and wires 64 and 26 back to battery 20. Thus, inasmuch as main amber lights 91 are already flashing and cross red lights 83 are flashed in the circuit just described, intermittently flashing warning signals 5 are directed in all directions, the cross-traffic being additionally warned of the dangerous highway intersection by the red color of the flashing cross red lights 83.

When selector switch 167 is moved so that 0 arm 166 engages contact 174 and arm 165 engages dead contact 171, the circuit to relay 49 is, of course, broken to restore normal contact between armature 80 and back contact 79 so that cross red lights 83 cease flashing, although the 5 main amber lights 91 continue to flash, as described. This new position of the selector switch 167 establishes a circuit traceable from battery 20 through wire 135, closed contacts 133 and 134 of cam 50, wire 150, terminal 153, switch arm 166, contact 174, wire 185, relay 76, and wires 139 and 26 back to battery 20. Energized relay 76 pulls its armature 77 out of engagement with back contact 75 and its armature 77' into engagement with front contacts 186. As relay contacts 186 are connected in parallel with relay 76, the branch circuit closed by armature 77' follows wire 78 to contact 79 of relay 49, armature 80, wire 82, cross red lights 83 and wires 64 and 26 back to battery 20. It will be seen that cross red 10 lights 83 shine steadily, while main amber lights 91 flash intermittently. Thus, cross traffic is brought to a stop at the intersection by the red lights 83, and main highway traffic is warned of the intersection ahead by the flashing main amber lights 91.

Thus it will be seen that a number of combinations of separate flashing warning signals may be energized after the master signal control system becomes inactive and the lamps are extinguished, and that these flashing warning signals continue until the master signal system appropriates control upon reclosing of cross street contacts 23 or 23' by a cross-traveling unit of traffic approaching the intersection.

Referring now to the system illustrated

diagrammatically in Fig. 2, let it be assumed that a cross-traveling vehicle approaching from the north closes street contacts 230. A circuit is established which is traceable from battery 2000 through wire 2001, contacts 230, wire 2002, relay 5 2003 and wire 2004 back to battery 2000. Relay 2003 is a slow-acting release or dash-pot relay, which remains closed for a duration of, say, three minutes, and when it is energized in the manner described its armature 2005 is pulled out of contact with back contacts 2006 and its armature 2005 bridges to front contacts 2007. The period during which the relay 2003 maintains its contacts 2007 closed is equal to the cycle of operation of the signal selecting mechanism, that is, to the time interval during which the commutators 2011, 2012, and 2013 complete a half revolution. The bridging of front contacts 2007 by the armature 2005 establishes a circuit from battery 2000, contacts 2007, armature 2005 of relay 20 2003, wire 2008, motor A and wires 2010 and 2022, back to battery 2000. Energization of motor A rotates commutators 2011, 2012 and 2013 to complete the signal cycle of both main and cross 25 traveling streets.

It will be recalled that the normal condition of the signal circuit just described maintains a closed signal circuit through the main green lights 2014 and cross red lights 2015. This circuit may be traced from battery 2000, wires 2001 and 2016, 30 brush 2017, live segment 2018 of commutator 2011, opposite live segment 2019, brush 2020, wire 2021, back contact 2065 of relay 2061, its armature 2064 and wires 2068 to main green lights 2014 and cross red lights 2015, and back to battery 2000 35 by way of wire 2022.

Rotation of motor A' and the consequent rotation of commutators 2011, 2012 and 2013 causes the traffic signals to flash through the signal cycle as follows: As brushes 2017 and 2020 ride off 40 the live segments 2018 and 2019, respectively, of commutator 2011, brushes 2023 and 2024 ride upon the live segments 2025 and 2026, respectively, of commutator 2012. This establishes a circuit traceable from battery 2000, wires 2001 45 and 2069, brush 2023, live segment 2025 of commutator 2012, live segment 2026, brush 2024, wire 2027, back contact 2028 of relay 2029, its armature 2030, wire 2031, cross amber lights 2032 and main amber lights 2033, and back to battery 2000 50 by way of wire 2022. Accordingly, the amber warning lights are flashed against both main and cross traveling vehicles.

These amber lights are maintained illuminated for a predetermined time, which is determined 55 by the length of the live segments 2025 and 2026 of commutator 2012. Obviously, by lengthening the live segments of commutator 2012, the times of illumination of the amber lights may be extended so that they will be illuminated before 60 the red or green lights are extinguished and will be extinguished after the red and green lights are illuminated, and the like. After the brushes 2023 and 2024 move off of these live segments, brushes 2034 and 2035 of commutator 2013 move 65 upon the respective live segments 2036 and 2037 of commutator 2013. This establishes a circuit traceable from battery 2000, wires 2001 and 2009, brush 2034, live segment 2036 of commutator 2013, live segment 2037, brush 2035, back contacts 2038 70 of relay 2039, its armature 2072, wire 2040, cross green lights 2041, main red lights 2042, and wire 2022 back to battery 2000. The main red lights 2042 are accordingly displayed against main highway traffic to stop it, so that the cross traveling 75

vehicle, which originally initiated the circuit just traced by closing contact 230 may cross the main highway in response to the illumination of cross green lights 2041. After a predetermined interval sufficient to permit the cross-traveling vehicle to negotiate the main highway, brushes 2034 and 2035 ride off of the respective live segments 2036 and 2037 of commutator 2013 and extinguish main red lights 2042 and cross green lights 2041. At the same time brushes 2023 and 2024 ride upon the respective live segments 2025' and 2026' of commutator 2012, and the main amber lights 2033 and the cross amber lights 2032 shine for an interval in the manner previously described. Then the brushes 2017 and 2020 ride upon the respective live segments 2019 and 2018 of commutator 2011 at the time that the slow-acting relay 2003 or other suitable timing mechanism opens to stop motor A' and restores the original circuit to provide a steady green light on a main highway and a steady red light on the cross street. Also the armature 2005 of slow-acting relay 2003 is disconnected from front contacts 2007 and the armature 2005' is returned by spring 2043 into bridging contact with back contacts 2006.

This normal condition of relay 2003 effects the initiation of a flashing circuit which intermittently also flashes the main and cross amber lights to warn traffic approaching on each street that a traffic control zone is ahead. When line switch 2044 is closed, a circuit is established by the closing of contacts 2006 of relay 2003 and this circuit may be traced from battery 2000, wire 2001, back contacts 2006 of relay 2003, armature 2005', wire 2046, line switch 2044, wire 2045, where the circuit divides, one branch passing through motor B', whose circuit is completed by wires 2048 and 2022 to battery 2000. The consequent rotation of motor B' also rotates cam 2050, whose follower 2051 is accordingly raised and lowered into and out of engagement with one of the contacts 2052. A condenser 2047 connected in parallel with the contacts 2052 prevents arcing between them as they are separated by cam 2050. Engagement of contacts 2052 establishes the other branch circuit from wire 2045 and this branch circuit includes make-and-break contacts 2052, wire 2054, terminal 2055, where the circuit divides and one branch of this divided circuit follows wire 2056 to normally open front contacts 2057 of relay 2029, from which the circuit is completed through the electrically connected armatures 2030' and 2030 of relay 2029, wire 2031, cross amber lights 2032 and main amber lights 2033 through wire 2022 to battery 2000. The other branch from terminal 2055 leads to manual selector switch arm 165'.

The manual selector switch 154' is identical to the manual selector switch illustrated in Fig. 1 and described heretofore and has the adjusting handle 168' mounted on the bar 167' connecting the two pivoted contactor arms 165' and 166'. In the position shown in Fig. 2, arm 165' of this switch 154' engages dead contact 169', while the other arm 166' thereof engages contact 172' so that a circuit is completed from battery 2000, wires 2001 and 2046, wire 2048, switch arm 166', contact 172', wire 2059, relay 2029 and wires 2058 and 2022, back to battery 2000. The energized relay 2029 pulls down armatures 2030 and 2030' to break the connection between armature 2030 and back contacts 2028 and complete the connection between armature 2030' and front contacts 2057. This connects the flashing circuit with wire 2031, main amber lights 2033 and cross amber lights

2032, and the circuit is completed by way of wire 2022 back to battery 2000. Main amber lights 2033 and cross amber lights 2032 accordingly flash in all directions, while main green lights 2014 and cross red lights 2015 shine steadily. This flashes a warning signal in all directions to warn traffic approaching on main and, cross streets that an intersection under traffic control lies ahead, though only the cross traffic is stopped. 5

If the manual selector switch 154' is moved so that its arm 166' engages contact 173', and its other arm 165' engages contact 170', a new flashing circuit is established. The circuit is traceable from battery 2000, through wire 2001, contacts 2006 of relay 2003, its armature 2005', wires 2046 and 2049, switch arm 166', contact 173', wire 2060, relay 2061, and wires 2062 and 2022 back to battery 2000. Energized relay 2061 pulls down its armatures 2063 and 2064 to break the normal contact between armature 2064 and contact 2065, and connect front contacts 2066 to armature 2063. This establishes a circuit traceable from flashing circuit terminal 2055, through switch arm 165', contact 170', wire 2067, front contact 2066 of relay 2061, armature 2063, wire 2068 to main green lights 2014 and cross red lights 2015, and back to battery by way of wire 2022.

Normally steady main green lights 2014 and cross red lights 2015 are now flashed intermittently to stop cross traffic and main highway traffic is additionally warned by the flashing green light that, although the right of way is clear, traffic must watch out for cross traveling vehicles which seek to enter the main highway at the intersection. 35

When manual selector switch 154' is manipulated so that arm 166' engages contact 174' and arm 165' engages contact 171', a new flashing circuit is established and the circuit previously traced is broken, although the consequent de- 40 energization of relay 2061 completes the normal circuit to main green lights 2014 and cross red lights 2015 through the now closed back contacts 2065 of relay 2061 in the manner previously described. Accordingly, when manual selector 45 switch 154' is disconnected completely from any of the contact points, the system lapses into its normal condition just described. However, when contacts 174' and 171' are engaged by the corresponding arms of the switch 154', two circuits, one 50 of which is a flashing circuit, are completed. The first circuit is traceable from battery 2000 by way of wire 2001, contacts 2006 of relay 2003, its armature 2005', wires 2046 and 2049, switch arm 166', switch contact 174', wire 2070, relay 2039, and wires 2071 and 2022 back to battery 2000. The consequent energization of relay 2039 causes its armature 2072 to break contact with contacts 2038 and bridge contacts 2073. This establishes a second or flashing circuit traceable from terminal 60 2055, switch arm 165', contact 171', wire 2074, front contacts 2073 of relay 2039, armature 2072, wire 2040, cross green lights 2041, and main red lights 2042, and by way of wire 2022 back to battery 2000. 65

It will be observed that, in addition to the steady main green light 2014, the main cross light 2042 flashes intermittently, thus serving as a warning to main highway traffic that, although the right of way is open, an intersection is being approached. Likewise, although cross red lights 2015 are steady, the flashing cross green lights 2041 indicate that the intersection may be negotiated by the cross-traveling vehicle upon closing of the street contact 230 or 230'. 70 75

In any case, the intermittent flashing signals are instantly interrupted the moment a cross-traveling vehicle engages either contact 230 or 230'. That is so, because closing of each one of these street contacts immediately energizes slow-acting relay 2003, or the equivalent timing mechanism, so that the normal connection between contacts 2006 is instantly broken to stop the rotation of motor B', which is the flashing circuit 10 motor, and the connection between contacts 1007 is made to start motor A' of the master signal system.

Means is provided for converting the signal systems into a continuously operating system at will. 15 This means is illustrated in Fig. 1 and may be duplicated in the arrangement of Fig. 2 and consists of a locking switch 18, which is connected in parallel with one of the street contacts 23 for short circuiting the same at will. When this 20 switch 18 is closed, the flashing signal mechanism becomes ineffective because the motor A, or the motor A' in Fig. 2, rotates continuously to drive the switches through the alternate signal cycles.

Also as illustrated in Fig. 1, the duration of 25 the signal cycle may be varied at will to meet various operating conditions by means of the variable resistance 44' in the circuit of the timing motor A. A similar variable resistance 141' in the circuit of flasher motor B permits regulation 30 of the time between flashes. A similar variable resistance may be placed in the circuit of flasher motor B' of the arrangement of Fig. 2.

It will be seen that the new automatic traffic 35 regulating system of this invention provides the normally inactive types of master traffic control systems with an auxiliary warning signal which is operative during the intervals that the master signal control system is inactive. Accordingly, dangerous intersections are always identified by 40 a flashing signal to warn approaching vehicles that traffic may suddenly turn into the main highway from a cross street at the intersection. This is especially important when both of the master signal control systems heretofore described are employed, for the reason that the 45 clear signal or no signal at all is indicated to the main highway traffic, which accordingly progresses at high speed without regard to cross traffic. Likewise, many cross traveling vehicles 50 will attempt to negotiate the main highway, either by turning into it or cross it, without waiting for the signal system which has been initiated by the cross traveling vehicle to become sufficiently advanced to indicate the clear signal to 55 the cross-traveling vehicle and stop the main highway traffic. In general, the manual selector switch will be so positioned that the amber or caution lights flash intermittently in all directions when the master signal system is in its 60 normally inactive condition, whether or not its lights or other signals are normally extinguished or indicate a clear signal to main highway traffic and a stop signal to cross traffic. However, in certain conditions it may be necessary or ad- 65 visable to procure different combinations of the flashing signal, such as the flashing green light directed to the main highway traffic together with a flashing red light directed against cross-traveling traffic; combinations of steady green 70 or red lights with corresponding flashing red or green lights; a steady red or green light indicated in another direction and a flashing green or red light indicated in another direction, and the like. In short, many combinations of flashing lights may be procured by manipulating the 75

master selector switch to various contacting positions and arranging the connection in such a way as to secure any desirable combination.

The new flashing arrangement protects the intersection even if the street contacts should fail 5 for any reason and not initiate the signal cycle because the flashing signal warns all who seek to cross of the danger. Also if a vehicle is parked between the street contact and the intersection in such a way that a following vehicle cannot 10 gain access to the street contact, the following vehicle can nevertheless proceed with reasonable safety without benefit of the normal signal lights, because the flashing signal cautions other approaching vehicles of the danger of the intersection. Again, a vehicle last crossing a street contact just before the expiration of the maximum signal time allowed the traffic on his street would be stranded unless he backed up over the contact or waited for a following vehicle to actuate the contact in the former systems, but the flasher of this system provides him with reasonable safety so that he may cross without first backing up to actuate the contact or waiting for a following vehicle to actuate it for him. The 25 same condition results if a vehicle moves so far to the left as to avoid the contact, as when starting to make a left turn or the like.

While a preferred embodiment of the invention has been illustrated and described herein 30 it is to be understood that the invention is not limited thereby, but is susceptible of many changes in form, detail and arrangement within its scope.

In the following claims it will be understood 35 that the expressions "signal cycle" and "signalling cycle" refer to the usual traffic control cycle wherein "stop" and "go" signals are alternately displayed to a street or streets of an intersection for predetermined periods of time for the control 40 of traffic at the intersection with each signal continuously illuminated during its display period, and in which a caution signal may or may not be interposed between successive displays of the "stop" and "go" signals. 45

I claim:

1. In a traffic regulating system for a street intersection, the combination of a plurality of separate signals in individual circuits, normally inactive switching mechanism capable upon operation of successively energizing the circuits of said signals to complete a single signal cycle and then stop, vehicle-actuated means in at least one of the streets for energizing said switching mechanism, an independent circuit including at 55 least one of said signals, means actuated by said switching mechanism upon completion of the signal cycle for energizing said independent circuit and an interrupter in said independent circuit for making and breaking the same to intermittently energize said one signal, the operation of said last-named means continuing until interrupted by said mechanism in response to re-actuation of the vehicle-actuated means. 60

2. In a traffic regulating system for a street 65 intersection, the combination of a plurality of separate signals in individual circuits, normally inactive switching mechanism capable upon operation of successively energizing the circuits of said signals to complete a single signal cycle, and then stop, vehicle-actuated means in at least one of the streets for energizing said switching mechanism, an independent circuit including a plurality of said first signals, means actuated by said switching mechanism upon completion of 70 75

- the signal cycle for energizing said independent circuit, and an interrupter in said independent circuit for making and breaking the same to intermittently energize said last signals, the operation of said last-named means continuing until interrupted by said mechanism in response to reactivation of the vehicle-actuated means.
3. In a traffic regulating system for a street intersection, the combination of a plurality of separate signals in individual circuits, normally inactive switching mechanism capable upon operation of successively energizing the circuits of said signals to complete a single signal cycle and then stop, vehicle-actuated means in at least one of the streets for energizing said switching mechanism, an independent circuit having branches leading to a plurality of said signals, means actuated by said switching mechanism upon completion of the signal cycle for energizing said independent circuit, and selective means controlling said branch circuits for selecting certain of said signals for energization, the operation of said last-named means continuing until interrupted by said mechanism in response to reactivation of the vehicle-actuated means.
4. In a traffic regulating system for a street intersection, the combination of a plurality of separate signals in individual circuits, normally inactive switching mechanism capable upon operation of successively energizing the circuits of said signals to complete a single signal cycle and then stop, vehicle-actuated means in at least one of the streets for energizing said switching mechanism, an independent circuit having branches leading to a plurality of said signals, means actuated by said switching mechanism upon completion of the signal cycle for energizing said independent circuit, selective means controlling said branch circuits for selecting certain of said signals for energization, and an interrupter in said independent circuit for intermittently making and breaking the branch circuit selected by said selective means for intermittently energizing the corresponding signals, the operation of said last-named means continuing until interrupted by said mechanism in response to reactivation of the vehicle-actuated means.
5. In a traffic regulating system for a street intersection, the combination of a plurality of separate signals in individual circuits, normally inactive switching mechanism capable upon operation of successively energizing the circuits of said signals to complete a single signal cycle and then stop, vehicle-actuated means in at least one of the streets for energizing said switching mechanism, and means independent of said switching mechanism but initiated thereby upon completion of the signal cycle for intermittently reenergizing a plurality of said signal circuits to intermittently energize the signals thereof, the operation of said last-named means continuing until interrupted by said mechanism in response to reactivation of the vehicle-actuated means.
6. In a traffic regulating system for a street intersection, the combination of a plurality of separate signals in individual circuits, normally inactive switching mechanism capable upon operation of successively energizing the circuits of said signals to complete a single signal cycle, and then stop, vehicle-actuated means in at least one of the streets for energizing said switching mechanism, means independent of said switching mechanism but initiated thereby upon completion of the signal cycle for intermittently reenergizing a plurality of said signal circuits to in-
- termittently energize the signals thereof, the operation of said last-named means continuing until interrupted by said mechanism in response to reactivation of the vehicle-actuated means and devices interposed between said last-named means and said signals for disconnecting any of said signals, whereby only selected signals are intermittently energized and deenergized.
7. In a traffic regulating system for a street intersection, the combination of "stop", "go" and caution signals in individual circuits, normally inactive switching mechanism capable upon operation of successively energizing the circuits of said signals to complete a signal cycle and then stop, vehicle actuated means in at least one of the streets for energizing said switching mechanism, and means independent of said mechanism but initiated thereby upon completion of the signal cycle for intermittently energizing the caution signal circuit to intermittently energize the caution signal, the operation of said last-named means continuing until interrupted by said mechanism in response to reactivation of the vehicle-actuated means.
8. In a traffic regulating system for a street intersection, the combination of at least two sets of a plurality of signals directed in different directions, individual signals of each set being included in one of a plurality of circuits, switching mechanism capable upon operation of successively energizing the said circuits to complete a signal cycle and then stop, vehicle actuated means in at least one of the streets for energizing said mechanism, and means independent of said mechanism but initiated thereby upon completion of the signal cycle for intermittently making and breaking one of said circuits to intermittently energize and deenergize signals in both of said different directions, the operation of said last-named means continuing until interrupted by said mechanism in response to reactivation of the vehicle-actuated means.
9. In a traffic regulating system for a street intersection, the combination of at least two sets of a plurality of signals directed in different directions, individual signals of each set being included in one of a plurality of circuits, switching mechanism capable upon operation of successively energizing the said circuits to complete a signal cycle and then stop, vehicle actuated means in at least one of the streets for energizing said mechanism, auxiliary switching mechanism independent of said first named switching mechanism but initiated thereby upon completion of the signal cycle for reenergizing one of said circuits, and an interrupter actuated by said auxiliary switching mechanism for interrupting said one circuit to intermittently energize signals in both of said different directions, the operation of said auxiliary mechanism continuing until interrupted by said mechanism in response to reactivation of the vehicle-actuated means.
10. In a traffic regulating system for a street intersection, the combination of at least two sets of a plurality of signals directed in different directions, individual signals of each set being included in one of a plurality of circuits, switching mechanism capable upon operation of successively energizing the said circuits to complete a signal cycle and then stop, vehicle actuated means in at least one of the streets for energizing said mechanism, and means independent of said mechanism but initiated thereby upon completion of the signal cycle for intermittently making and breaking one of said circuits to intermittently energize and de-

energize signals in both of said different directions, the operation of said last-named means continuing until interrupted by said mechanism in response to reactivation of the vehicle-actuated means, and a manual selector switch for connecting said last-named means to any of said circuits to intermittently energize selected signals.

11. A traffic regulating system located at the intersection of at least two traffic lanes including signal lamp circuits for said traffic lanes, a time-controlled switch associated with said circuits for variably opening and closing the same to complete a signal cycle and then stop, said switch being normally idle in an initial position so that the system is normally inactive, means actuated by a vehicle approaching the intersection in at least one of the lanes for energizing said time-controlled switch, and means rendered effective by the restoration of said switch to its initial position for reenergizing at least one of said lamp circuits, said means including independently operative circuit interrupting mechanism for intermittently opening and closing the circuit of said one lamp for intermittently flashing the same, the operation of said last-named means continuing until interrupted by said mechanism in response to reactivation of the vehicle-actuated means.

12. A traffic regulating system for a street intersection including a pair of signal circuits, one circuit including a signal to indicate "stop" and the other to indicate "go", switch means movable through a signal cycle for alternately energizing said circuits, normally inactive time-controlled means for moving said switch means through its signal cycle, vehicle actuated means in at least one of the streets for rendering said time-controlled means active, means including the switch for restoring the time-controlled means to its inactive condition upon completion of only a single signal cycle, and mechanism independent of said last-named means but initiated thereby upon completion of the signal cycle for continuously making and breaking one of said circuits to intermittently energize the signal thereof, the operation of said mechanism continuing until stopped by said switching means in response to reactivation of the latter by said vehicle-actuated means.

13. A traffic regulating system for a street intersection including a pair of signal circuits, one circuit including a signal to indicate "stop" and the other to indicate "go", switch means movable through a cycle for alternately energizing said circuits, normally inactive time-controlled means for moving said switch means through its cycle, vehicle actuated means in at least one of said streets for rendering said time-controlled means active, means including the switch for restoring the time-controlled means to its inactive condition upon completion of only a single signal cycle, an independent signal circuit, mechanism rendered effective by said last-named means upon completion

of the signal cycle, and an interrupter actuated by said mechanism for making and breaking the said independent signal circuit and one of said first-named signal circuits, whereby the independent signal and said one first-named signal are simultaneously flashed intermittently, the operation of said interruptor continuing until stopped by said switch means in response to reactivation of the latter by said vehicle-actuated means.

14. A traffic control system for a street intersection, including a pair of signal circuits, one circuit including a signal lamp to indicate "stop" and the other a signal lamp to indicate "go", switching means operable through a signal cycle for alternately energizing said signal circuits and illuminating said signal lamps, normally inactive time-controlled means for moving said switching means through only a single signal cycle, vehicle-actuated means in at least one of the streets for rendering said time-controlled means active, means independent of the switching means but initiated thereby at the end of the timed cycle for deenergizing one of said circuits to extinguish the lamp thereof, an independently operative circuit interrupting mechanism, and an independent signal circuit including the other of said signal lamps and said interrupting mechanism, said independent circuit being energized by the initiation of said independent means to flash the signal lamp therein, the energization of said independent signal circuit continuing until deenergized by said switching means in response to reactivation of the latter by said vehicle actuated means.

15. A signalling system arranged at the intersection of a highway and a cross road for regulating traffic, said system including a highway signal lamp circuit and a cross-road signal lamp circuit, a time-controlled switch means in said circuits for alternately opening and closing the same, said switch being normally idle in an initial position so as to normally retain the highway circuit closed and permit highway traffic to cross the intersection, means actuated by a vehicle approaching the intersection on the cross road for actuating the switch so as to alternately energize said lamps and circuits continuously for predetermined periods to successively signal the right-of-way to the cross road and highway, said means including the time-controlled switch and being operative for automatically restoring the switch and the lamp circuits to their initial conditions upon completion of only a single signal cycle, and mechanism actuated by said last-named means upon completion of the signalling cycle for continuously interrupting at least one of said circuits to intermittently flash the lamp thereof, the operation of said mechanism continuing until interrupted by said switch means in response to reactivation of the latter by said vehicle-actuated means.

PAUL P. HORNI.
